UNITED STATES PATENT OFFICE.

WILLIAM HELLER, OF NEW YORK, N. Y.

DESIGN FOR A TEXTILE FABRIC.

Application filed March 16, 1928. Serial No. 25,888. Term of patent 3½ years.

To all whom it may concern:

Be it known that I, WILLIAM HELLER, a citizen of the United States, and resident of New York, county and State of New York, have invented a new, original, and ornamental Design for Textile Fabrics, of which the following is a specification, reference being had to the accompanying drawing forming a part thereof, and in which the figure is a plan view of a section of the fabric showing my new design.

I claim as my invention:

The ornamental design for a textile fabric, as shown.

WILLIAM HELLER.
